UNITED STATES PATENT OFFICE

JOHN E. SCOTT, OF DANVILLE, ILLINOIS, ASSIGNOR TO ALLITH-PROUTY COMPANY,
OF DANVILLE, ILLINOIS, A CORPORATION OF DELAWARE

DOOR CONSTRUCTION

Application filed May 24, 1930. Serial No. 455,202.

My invention relates to door construction and is principally concerned with structures of this kind which are supported and movable on swiveled rollers located in recesses formed in the thickness of the door, the type being exemplified in the doors employed to close the ends of airplane hangars.

One object of my invention is to devise weathering plates for enclosing the supporting roller to prevent passage of air and moisture through the roller recess to the interior of the hangar and to substantially hingedly carry each plate adjacent its upper edge, thereby providing relief for the roller as it moves out of the plane of the door in traversing curved portions of track.

A further object is to devise a manner of hinging the weathering plate which is characterized by a high degree of flexibility, permitting the plate to be moved bodily relative to its support on the door, or to partake of a movement which is a combination of a movement in the normal direction from the horizontal hinged connection and of a movement in a direction substantially at right angles thereto, or one which would correspond to a hinging of the plate along a vertical edge.

A further object is the provision of a slideable support for the weathering plate which permits it to be fulcrumed on the door along the adjacent plate edge during the hinging movement, the plate being returned to roller-enclosing position by spring action.

A further object is to support a pair of weathering plates on opposite sides of the door for covering the roller recess, the plates being supported vertically on pins slideable through the door and normally retained in position by springs extending between the plates at the same elevation as the pins.

Doors of the type for which the present invention is more specifically intended are roller mounted on trackways at their lower edges and suitably guided at their upper edges, and in moving from closed to open position, the rollers traverse curves to place the door adjacent the side walls of the hangar. These rollers are mounted in suitable recesses within the thickness of the door and are vertically swiveled to permit their following

the track surfaces, which movement causes them to assume a canted position relative to the plane of the door. As the operating requirements of the hangar necessitates the use of weathering plates to cover the roller recesses for preventing passage of wind, snow and rain therethrough, it follows that these plates must be arranged for a relieving or accommodating movement during the traversing of the curve by the roller, the latter 55 preferably contacting with the plates to move them outwardly. It is one of the express objects of the present invention to hinge the plates for the above movement and to arrange the connections in such a manner that 60 the engagement of the plates while in an outward position with banked snow, for example, will not cause a further opening movement thereof and possible fracture of the parts during the continued movement of the door. 65 The hinging of the door along its upper edge enables the leading edge of the weathering plate to act substantially as a knife edge and to readily cut through an obstruction of the above nature while occupying a displaced or 70 canted position relative to the door. 75

These and further objects of my invention will be set forth in the following specification, reference being had to the accompanying drawings, and the novel means by which 80 said objects are effectuated will be definitely pointed out in the claims.

In the drawings:

Figure 1 is a side elevation of the lower corner of a door embodying the improvements of the present invention.

Fig. 2 is an enlarged section taken along the line 2-2 in Fig. 1, looking in the direction of the arrows, and showing the manner of supporting the weathering plates on the door for a hinging movement.

Figs. 3 and 4 are sections along the lines 3-3 and 4-4, respectively of Fig. 2, looking in the direction of the arrows, and showing the supporting and spring-retaining details 85 for the weathering plate structure.

Fig. 5 is an enlarged view similar to that shown in Fig. 1, one of the weathering plates being partially broken away to show the supporting structure for the door.

Fig. 6 is a section along the line 6—6 in Fig. 5, looking in the direction of the arrows, and showing in edgewise view the weathering plates on opposite sides of the supporting roller.

Fig. 7 is a section along the line 7—7 in Fig. 6, looking in the direction of the arrows, the roller being shown in the position which it assumes while traversing a curved 10 portion of the track with the weathering plates assuming an accommodating position therefor.

Fig. 8 is an end view of the door while in the position shown in Fig. 7, the door being 15 viewed in the direction of the arrow 8 in said last figure.

Referring to Figs. 1 and 5, the numeral 10 designates a door which may be formed by a plurality of vertical standards 11—11, 20 spaced from each other and of which only two are shown in said figures. These standards are preferably of tubular construction and the two which are shown in Figs. 1 and 5 are spaced apart by a brace 12 which is disposed 25 a predetermined distance above the lower edge of the door to form a recess 13. The outer and inner faces of the standards 11 have attached thereto cover plates 14 and 15, which are fixed in position and cover the 30 entire surface of the door except the recess 13 which is enclosed by plates hereinafter described. The recess 13 is utilized to receive a supporting roller for the door which moves along a suitable trackway, all of these parts 35 being described hereinafter, and it will further be understood that the end of an airplane hangar is enclosed by a plurality of the doors 10, as described more fully in my co-pending application, Serial No. 378,868, filed 40 July 17, 1929.

Located within the upper end of the recess 13 is a frame 16 having oppositely extending arms 17 which seat against the opposed inner faces of the standards 11, 11 and 45 are secured thereto by means of bolts 18 and 19 (see Fig. 5). The frame 16 is employed as a means of roller support and to that end, a spindle 20 is journaled in a bearing 21 formed in the lower portion of said frame 50 and said spindle threadedly receives the lower end of a stem 22 whose upper end is journaled in a bearing 23 provided in the upper end of the frame 16. The stem 22 is provided with an enlarged, wrench-receiving 55 head 24, by means of which the vertical position of the spindle 20, and accordingly the supporting roller as hereinafter described, may be adjusted to maintain the door 10 a predetermined distance above the 60 ground and the adjustment so made may be locked by a nut 25. However, the vertical adjustment of the spindle 20 forms no part of the present invention and other devices for achieving the same result may be adopted as 65 desired. The lower end of the spindle 20 has

provided thereon a saddle 26 having a pair of spaced, depending, side members 27 through which extends transversely an axle 28 for a supporting roller 29. Said roller is preferably of a dual flanged type and normally runs upon a track 30, whereby the door 10 may be moved from position to position as desired.

In order to adequately house the supporting roller 29 and to prevent the passage of wind and rain through the recess 13 into the interior of the hangar, a pair of weathering plates 31 and 32 are substantially hingedly connected to the door 10 on opposite sides thereof for the purpose of accommodating the swiveling action of the roller 29 as it traverses the curved portions of the track 30, the plate 31 being secured to the outer face of the door 10 and the plate 32 to the inner face thereof. Specifically, and referring to 75 Figs. 5 and 6, the plates 31 and 32 are provided with flat portions 33 and 34, respectively, along their upper edges and said portions normally seat against the opposite side faces of the brace 12. A predetermined distance 80 below said portions, the plates 31 and 32 are slightly offset therefrom and have attached to their respective inner faces brackets 35 and 36. Each plate has a pair of said brackets in spaced relation to each other, with the 85 brackets 35 being positioned between the brackets 36, as shown clearly in Fig. 2. All of said brackets are secured to the indicated weathering plates at substantially the same elevation and to the brackets 35 are pivotally 90 secured one end of pins 37 which are loosely reciprocable within holes 38 provided in the frame 16. Similarly, one end of a pin 39 is pivotally secured to each of the brackets 36 and said pins are loosely reciprocable 95 within holes 40 also provided in the frame 16. The longitudinal axes of the pins 37 and 39 lie in the same horizontal plane and said pins constitute the sole vertical support for their respective weathering 100 plates. Below said pins, the weathering plates 31 and 32 extend downwardly to completely cover the recess 13, and at their lower edges, the plates may have secured thereto a retaining strip 41 for the purpose of holding 105 a depending skirt 42 which may be formed of any suitable flexible material, such as rubber, canvas, and the like, and which depends further from each of the plates in substantial continuation thereof to a predetermined 110 distance below the head of the track 30, thereby completely closing the opening between the lower edge of the door 10 for the width of each of the weathering plates and the head of said track. A similar retaining strip 43 and skirt 44 may be attached to the remainder 115 of the lower edge of said door, as shown in Fig. 1.

In order to retain the weathering plates 31 and 32 in the normal positions shown in 120

Figs. 1 and 6 and to insure their return to said positions after being displaced therefrom as described more fully hereinafter, springs 45 are employed which yieldingly retain the plates 31 and 32 in recess enclosing position, one end of each of said springs being looped over a hook 46 provided on the inner face of the plate 32 and the opposite end of said spring being looped over a hook 47 provided on the inner face of the plate 31. Said springs are preferably of the helical type and their longitudinal axes preferably lie in the same plane with the longitudinal axes of the pins 37 and 39 for a purpose hereinafter explained.

In operation, the weathering plates 31 and 32 will be substantially retained in the vertical positions shown in Fig. 6, so long as the roller 29 traverses straight portions of the track 30, but as it enters upon a curved portion of said track and during its occupancy thereof, it will, owing to its swivel attachment to the frame 16 and accordingly with the door 10, assume an angular, or canted, position with reference to the vertical plane of said door, as shown in Fig. 7. Assuming that the roller 29 is moving in the direction of the arrow 48 in Fig. 7, it will be apparent that the leading, inner circumferential edge of said roller will bear against the inner face of the weathering plate 32 and that the trailing, outer circumferential edge of said roller will bear against the inner face of the plate 31, thereby moving the lower edges of said plates outwardly to substantially assume the position indicated in Fig. 7. During these movements of said plates, their vertical support is maintained by the pins 37 and 39 as they are laterally displaced from the position shown in Figs. 2 and 6, and the fulcrum for these movements of the plates 31 and 32 will exist substantially along their respective upper edges 49 and 50 which bear against the sides of the brace 12. The displaced movements of said plates are made against the resistance offered by the springs 45, the plates operating against each other in this respect, and when the roller 29 again enters upon a straight portion of the track 30, said plates will be returned to roller enclosing position by said springs. It will be observed that the disposition of the springs and the pins in substantially the same horizontal plane and the loose mounting of the latter in the frame 16 enables the plates 31 and 32 to be freely moved for an adequate distance without any binding of said pins in the frame 16. Further, the foregoing manner of hinging the plates on the door insures that an accumulation of banked snow before either of said plates while the roller 29 is traversing a curved portion of the track 30 will not cause the plates to be opened further by the pressure thereby established, or a movement which would correspond generally

to a hinging of these plates along one vertical edge thereof. The hinging of each weathering plate along an upper edge thereof further enables each side edge of said plate to function substantially as a knife edge in meeting an obstruction of the above nature, while occupying a displaced position, so that the door of the present invention is moved easier and with less possibility of damage to the several parts. A further notable advantage of the manner of hinging the door, as discussed above, is the flexible nature of the hinge mounting, involved in the use of loosely, slidable pins which operate as the vertical support for the plates. These pins enable each of the plates to be moved laterally from the door, or each plate may even assume a position, within suitable limits, in which the upper edge thereof is angularly disposed to the side of the brace 12, so that the weathering plates 31 and 32 are characterized by a more flexible type of hinge mounting than now prevails in doors of the type indicated.

While I have shown one set of elements and combinations thereof for effectuating my improved door construction, it will be understood that the same is intended for purpose of illustration only and in no wise to restrict my device to the exact forms and structures shown, for many changes may be made therein without departing from the spirit of my invention.

I claim:

1. The combination of a door including a recess, a roller swiveled in said recess about an axis transverse to its axis of rotation for supporting the door along a trackway, a weathering plate covering said recess, and means for hingedly connecting said plate to the door along the upper edge of said recess for accommodating swiveling movements of said roller.

2. The combination of a door including a recess, a roller swiveled in said recess about an axis transverse to its axis of rotation for supporting the door along a trackway, a weathering plate covering said recess, means for hingedly connecting said plate to the door along the upper edge of said recess for accommodating swiveling movements of said roller, and means for returning said plate to recess-covering position.

3. The combination of a door including a recess, a roller swiveled in said recess about an axis transverse to its axis of rotation for supporting the door along a trackway, a weathering plate covering said recess, means for hingedly connecting said plate to the door along the upper edge of said recess for accommodating swiveling movements of said roller, and spring means for returning said plate to recess-covering position.

4. The combination of a door including a recess, a roller swiveled in said recess about an axis transverse to its axis of rotation for

- supporting the door along a trackway, a weathering plate covering said recess, and means for connecting said plate to the door for pivotal movement, said pivoting occurring along the door contacting edge of the plate adjacent said connecting means. 5
5. The combination of a door including a recess, a roller swiveled in said recess about an axis transverse to its axis of rotation for supporting the door along a trackway, a weathering plate covering said recess, means for connecting said plate to the door for pivotal movement, said pivoting occurring along the door contacting edge of the plate adjacent said connecting means, and means for returning said plate to recess-covering position. 10
6. The combination of a door including a recess, a roller swiveled in said recess about an axis transverse to its axis of rotation for supporting the door along a trackway, and a weathering plate covering said recess, said plate being supported in one location on said door and pivoted at another. 20
7. The combination of a door including a recess, a roller swiveled in said recess about an axis transverse to its axis of rotation for supporting the door along a trackway, a weathering plate covering said recess, said plate being supported in one location on said door and pivoted at another, and means located in the plane of the plate support for returning said plate to recess-covering position after a pivotal movement. 30
8. The combination of a door including a recess, a roller swiveled in said recess about an axis transverse to its axis of rotation for supporting the door along a trackway, and a pivotal, weathering plate covering said recess and mounted on said door adjacent an edge of said plate for lateral movement bodily, the pivotal movement of said plate occurring along said edge as a fulcrum on said door. 40
9. The combination of a door including a recess, a roller swiveled in said recess about an axis transverse to its axis of rotation for supporting the door along a trackway, and a pivotal, weathering plate covering said recess and yieldingly mounted on said door adjacent an edge of said plate for lateral movement bodily, the pivotal movement of said plate occurring along said edge as a fulcrum on said door. 50
10. The combination of a door including a recess, a roller swiveled in said recess about an axis transverse to its axis of rotation for supporting the door along a trackway, a pivotal, weathering plate covering said recess, and pins, each connected at one end to said plate adjacent an edge thereof, loosely mounted in said door, the pivotal movement of said plate occurring along said edge as a fulcrum on said door and said pins being partially retractile during said movement. 60
11. The combination of a door including a recess, a roller swiveled in said recess about an axis transverse to its axis of rotation for supporting the door along a trackway, a pivotal weathering plate covering said recess, pins, each connected at one end to said plate adjacent an edge thereof, loosely mounted in said door, the pivotal movement of said plate occurring along said edge as a fulcrum on said door and said pins being partially retractile during said movement, and springs means located in the plane of said pins for returning said plate to recess-covering position. 70
12. The combination of a door including a recess, a roller swiveled in said recess about an axis transverse to its axis of rotation for supporting the door along a trackway, a pair of pivotal, weathering plates for covering opposite sides of said recess and mounted on opposite sides of said roller adjacent an edge of each of said plates for lateral movement bodily, the pivotal movement of each of said plates occurring along said edge as a fulcrum on said door. 80
13. The combination of a door including a recess, a roller swiveled in said recess about an axis transverse to its axis of rotation for supporting the door along a trackway, a pair of pivotal, weathering plates for covering opposite sides of said recess and yieldingly mounted on opposite sides of said door adjacent an edge of each of said plates for lateral movement bodily, the pivotal movement of each of said plates occurring along said edge as a fulcrum on said door. 90
14. The combination of a door including a recess, a roller swiveled in said recess about an axis transverse to its axis of rotation for supporting the door along a trackway, a pair of pivotal, weathering plates for covering opposite sides of said recess and yieldingly connected to each other, each of said plates being mounted on said door adjacent an edge of said plate for lateral movement bodily, the pivotal movement of each plate occurring along said edge as a fulcrum on said door. 100
15. The combination of a door including a recess, a roller swiveled in said recess about an axis transverse to its axis of rotation for supporting the door along a trackway, a pair of pivotal, weathering plates for covering opposite sides of said recess, and pins connected to each plate adjacent an edge thereof loosely mounted in said door, the pivotal movement of each plate occurring along the respective edges thereof as a fulcrum on said door and said pins being partially retractile during said movement. 110
16. The combination of a door including a recess, a roller swiveled in said recess about an axis transverse to its axis of rotation for supporting the door along a trackway, a pair of pivotal, weathering plates for covering opposite sides of said recess, pins connected to 120
17. The combination of a door including a recess, a roller swiveled in said recess about an axis transverse to its axis of rotation for supporting the door along a trackway, a pair of pivotal, weathering plates for covering opposite sides of said recess, pins connected to 130

each plate adjacent an edge thereof loosely mounted in said door, the pivotal movement of each plate occurring along their respective edges as a fulcrum on said door and said pins 5 being partially retractible during said movement, and springs means located in the plane of said pins for returning said plates to recess-covering position.

17. The combination of a door including 10 a recess, a roller swiveled in said recess about an axis transverse to its axis of rotation for supporting the door along a trackway, a weathering shield covering said recess, and means for connecting said shield to said door 15 for swinging movement about a horizontal line whereby the lower edge of said shield is moved outwardly from said door to accommodate swiveling movement of said roller.
- 20 18. The combination of a door including a recess, a roller swiveled in said recess about an axis transverse to its axis of rotation for supporting the door along a trackway, a weathering shield covering said recess, and 25 means adapted to horizontally connect said shield to said door for swinging movement adjacent the upper end of said recess whereby the lower edge of said shield is moved outwardly from said door to accommodate swiveling movement of said roller.

In testimony whereof, I have subscribed my name.

JOHN E. SCOTT.
